(57) **CLAIM**

We claim the ornamental design for a biker's belt, as shown and described.

DESCRIPTION

FIG. 1 is a perspective view of a biker's belt showing our new design;

FIG. 2 is a inner side elevational view thereof;

FIG. 3 is an outer side elevational view thereof;

FIG. 4 is a top plan view thereof, the bottom plan view being identical thereto;

FIG. 5 is an end elevational view thereof; and,

FIG. 6 is a elevational view of the opposing end thereof.

1 Claim, 3 Drawing Sheets

FIG. 1.

FIG. 3.

FIG. 6.
